THREADING-IN ON A REEL

Ernest J. Griset, Jr., Asheville, N. C., assignor to
American Enka Corporation, Enka, N. C., a corporation of Delaware

Application March 3, 1952, Serial No. 274,532

6 Claims. (Cl. 242—53)

1

This invention relates to the threading-in of skein winders and more particularly to a method and apparatus for the simultaneous threading-in of a plurality of running ends on a single reel of the type which concurrently winds a plurality of skeins.

Conventionally, a skein winding reel is threaded-in by winding loops around it at axially spaced points while it is held stationary and then, after all of the loops are in position, rotation of the reel is initiated to cause it to wind on itself a plurality of skeins. So long as the yarns or threads which are to be prepared in skein form are drawn from a static source such as a package or cake, the threading-in arrangement described above is quite satisfactory. On the other hand, when the threads are being continuously delivered in running form as by a continuous spinning machine, the threading-in of a skein winder of the type which winds a plurality of skeins on a single reel presents difficulties. The problems arise out of the necessity for taking care of the thread running to the loops already tied on the reel while the remainder are being tied.

It is therefore an object of this invention to provide for the convenient and easy threading-in of a skein winding reel with a plurality of running ends while minimizing waste of yarn and operator time.

Other objects and advantages of this invention will be apparent upon consideration of the following detailed description of an embodiment thereof in conjunction with the annexed drawings wherein;

Figure 1 is a view in elevation of a skein winding reel incorporating the improvements of the present invention;

Figure 2 is a view in cross section taken on the line 2—2 of Figure 1; and

Figure 3 is a view similar to Figure 2 but showing the reel in a difficult angular position to illustrate a different stage in the threading-in operation.

Referring now in greater detail to the drawings, the numeral 10 designates a skein winding reel of the type constructed to accommodate and wind six skeins simultaneously. The reel 10 is comprised of six spiders 11, 12, 13, 14, 15 and 16, axially equally spaced along a shaft 17. The shaft 17 is journaled in bearings 18 and 19 and is connected to be rotated by conventional mechanism, not shown.

Each spider is provided with six spokes radiating from a hub and, since the spider 13 is

typical of all of them both as to configuration and angular position on the shaft 17, only that spider is shown in end view.

The outer ends of the spokes of the spiders 11 to 16, inclusive, are connected to rods 20, 21, 22, 23, 24 and 25, which define with the spiders a cage-like structure. Each spider has associated with it a thread guide to lead the thread from a source, not shown, to the approximate plane of the approximate spider. These thread guides are identified in Figure 1 by numerals 11a to 16a, inclusive.

It will be understood that the skein winder thus far described is entirely conventional. As a part of the present invention each spider is provided with a stud 11b to 16b, inclusive, projecting from its side parallel to the shaft 17 and in a line between the tip of a spoke and the center line of the reel.

Associated with two of the spokes and the appropriate guide for each spider, there is a suction device which is capable of taking up a running yarn by exerting a pull thereon of constant magnitude sufficient to prevent slack but not enough to cause thread breakage. These devices which are indicated by reference numerals 26 to 31, inclusive, themselves form no part of the present invention being disclosed and described in copending application Serial No. 237,526, filed July 19, 1951.

Essentially, each of the suction devices 26 to 31, inclusive, comprises means defining a venturi and a notch in the housing for the venturi to permit thread access to the zone of reduced pressure and high velocity whereby a thread may be drawn into the device at its middle and projected out of the end to a point of waste collection.

The function of the present invention in the threading-in of a skein winding reel can be understood upon concurrent reference first to Figures 1 and 2 and then to Figures 1 and 3. The running yarns or threads issuing from sources not shown are led immediately to the appropriate suction device and are then dropped in the appropriate guide. Thus an initial thread path is established between the thread guide and each spider and the suction device for that spider. When all of the threads are running to the appropriate suction device, the operator draws a loop between the thread guide and the suction device and drops the running thread behind the projecting stud. See the broken line path of the thread in Figure 2. When all of the threads are running in accordance with the pattern depicted in broken lines in Figure 1, the reel is

caused to rotate in a counter-clockwise direction as it is viewed in Figures 2 and 3. The effect of this rotation is apparent in Figure 3 and as soon as sufficient overlapping has occurred to insure anchorage of one end of the thread on the reel, the thread or yarn is cut immediately adjacent the appropriate suction device as indicated at *x* in Figure 3.

From the above description it will be noted that an advantage of this invention resides in the fact that it is entirely unnecessary to wind any sort of loop about the skein-winding reel before the rotation of that reel is initiated. In other words, in threading-in, a condition is established which may be described as a condition precedent to the automatic formation of a loop, that condition precedent being depicted in broken lines in Figure 2. The condition is a stable one and affords ample time for the operator to get all of the threads so running before initiating rotation of the reel, and once rotation of the reel is commenced, all of the loops are wound at once and cutting of the threads running to the suction device can be quickly and easily accomplished.

What is claimed is:

1. Apparatus for threading-in a skein winder comprising a rotatable generally cylindrical reel defined by circumferentially spaced bars, a plurality of temporary collecting devices spaced apart in a line parallel to the reel axis, a plurality of thread guides also spaced apart in a line parallel to the reel axis, said guides and devices being disposed in pairs so that a straight line between them passes chordwise through the reel and so that thread running from the guide to the device contacts two bars of the reel, and a plurality of studs, one of said studs being disposed parallel to but radially inwardly of said bars adjacent the thread path between each guide and its respective temporary collecting device whereby in threading-in a running end is led to each guide and the temporary collecting device associated therewith, a loop is drawn between said two bars and passed around the respective stud and the reel is rotated to commence the winding of the skeins.

2. Apparatus for threading-in a skein winder comprising a rotatable generally cylindrical reel defined by circumferentially spaced bars supported by axially spaced spiders, a plurality of temporary collecting devices so spaced that one of the devices lies substantially in the plane of each spider but outside the periphery of the reel, a plurality of thread guides so spaced that one of the guides lies substantially in the plane of each spider but outside the periphery of the reel and on the other side of it from the respective device so that a straight line between each guide and the respective device passes chordwise

through the reel and thread passing from the guide to the device must follow a path in contact with at least two bars of the reel, a stud projecting axially from each spider at a point radially inwardly of said bars whereby in threading-in a running end is led to each guide and the temporary collecting device associated therewith, a loop is drawn between said two bars and passed around the respective stud and the reel is rotated to commence the winding of the skeins.

3. Apparatus as claimed in claim 2 in which the temporary collecting devices are of the suction device type imposing sufficient tension to prevent thread slack but not enough to cause breakage.

4. A method of threading-in a reel including circumferentially spaced bars around which a coil of thread is wound to form a skein that comprises initially establishing a running thread between a guide and a point of temporary collection around at least two bars of the reel, drawing the thread inwardly between the two bars and increasing the length of its path between said bars by guiding it at a point intermediate but inwardly of the bars, causing the reel to rotate and thereafter cutting the thread between the reel and the point of temporary collection.

5. A method of threading-in a reel including circumferentially spaced bars around which a plurality of coils of thread are wound to form skeins that comprises initially establishing a series of axially spaced running threads each in contact with at least two bars thereof, temporarily collecting each running thread individually, drawing a loop between the two contacted bars and re-establishing the running thread to a path moving inwardly and outwardly of the reel center in its passage between said two bars, thereafter causing the reel to rotate about a quarter turn and cutting the thread between the reel and the points of temporary collection.

6. A method of threading-in a reel including circumferentially spaced bars around which a plurality of coils of threads are wound to form skeins that comprises initially establishing a series of axially spaced running threads each in contact with at least two bars thereof, temporarily collecting each running thread individually at a point of suction sufficient to avoid slack but insufficient to induce breakage, drawing a loop between the two contacted bars and re-establishing the running thread to a path moving inwardly and outwardly of the reel center in its passage between said two bars, thereafter causing the reel to rotate about a quarter turn and cutting the thread between the reel and the points of temporary collection.
